UNITED STATES PATENT OFFICE

126,740

DESIGN FOR A TRAFFIC SIGNAL FOR AUTOMOBILES

Frank O. Bence, Chicago, Ill.

Application January 6, 1941, Serial No. 97,830

Term of patent 7 years

To all whom it may concern:

Be it known that I, Frank O. Bence, a citizen of the United States of America, residing at Chicago, in the county of Cook and State of Illinois, have invented a new, original, and ornamental Design for a Traffic Signal for Automobiles, of which the following is a specification, reference being had to the accompanying drawing, forming a part thereof.

Fig. 1 is a front elevational view of a design for a traffic signal for automobiles, showing my new design.

Fig. 2 is an elevational view looking at the right end of Fig. 1.

Fig. 3 is a rear view of the same.

Fig. 4 is a view looking at the end opposite that shown in Fig. 2.

Fig. 5 is a side elevational view thereof.

The dominant features of my design reside in the portions shown in full lines.

I claim:

The ornamental design for a traffic signal for automobiles, substantially as shown and described.

FRANK O. BENCE,
